UNITED STATES PATENT OFFICE

MILTON C. WILLIAMSON, OF ROCHESTER, NEW YORK, ASSIGNOR TO BAUSCH & LOMB
OPTICAL COMPANY, OF ROCHESTER, NEW YORK, A CORPORATION OF NEW YORK

DESIGN FOR A READING GLASS

Application filed January 7, 1930. Serial No. 34,043. Term of patent 7 years.

To all whom it may concern:

Be it known that I, MILTON C. WILLIAMSON, a citizen of the United States, and a resident of Rochester, county of Monroe, and State of New York, have invented a new, original, and ornamental Design for Reading Glass, of which the following is a specification, reference being had to the accompanying drawing, forming a part thereof.

Fig. 1 shows a perspective view of a reading glass, showing my new design.

Fig. 2 shows a top plan view of the same.

I claim:

The ornamental design for a reading glass substantially as shown.

MILTON C. WILLIAMSON.
